TOILET SEAT AND COVER HINGE

Harold D. Watson, Beloit, Wis.

Application December 19, 1941, Serial No. 423,569

4 Claims. (Cl. 4—236)

This invention relates to toilet seat and cover hinges.

It is an object of this invention to provide a hinge construction suitable for toilet seats and covers which is formed entirely of plastic material so as to lend itself more readily to harmonious color combinations and to obviate the unsightly corrosion which is inevitable where the hinge parts are made of metal.

An additional object of this invention is to provide an improved hinge construction for toilet seats and covers in which the seat and cover-carried hinge parts are provided with integral trunnions received in bearing sockets formed in the supporting standards or pedestals on the bowl.

A further object of this invention is to provide a hinge construction of the character described which is designed to relieve the trunnions of the hinges of substantially all strain incidental to the application of weight onto the lowered seat and cover, and to eliminate shearing stresses on any part of the hinge structure.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate several complete examples of the physical embodiments of the invention constructed in accordance with the best modes so far devised for the practical application of the principles thereof, and in which:

Figure 1 is a top plan view of a hinge construction embodying this invention, a part thereof being broken away and in section;

Figure 2 is a cross-sectional view taken through Figure 1 on the plane of the line 2—2;

Figure 3 is a cross-sectional view taken through Figure 1 on the plane of the line 3—3;

Figure 4 is a plan view similar to Figure 1 illustrating a modified form of the invention; and

Figure 5 is a cross-sectional view taken through Figure 4 on the plane of the line 5—5.

Referring now particularly to the accompanying drawings, in which like numerals indicate like parts, the numeral 3 designates the bowl of a toilet provided with the conventional seat 5 and cover 7.

The hinge construction of this invention con-

sists of a pair of spaced similar but opposite bearing standards 30; a cover hinge member 34 and a pair of seat hinge members 39.

All of these parts are formed of plastic material so that they may be provided in colors to match any desired color scheme. The use of plastic material also overcomes the objectionable discoloration caused by corrosion to which metal hinge parts are subject.

10 The bearing standards are secured to the top surface 11 of the bowl at the customary location of the hinge by means of studs 12 embedded in the bearing standards and passing through holes in the flange of the bowl to have nuts (not shown) threaded thereon and drawn up against the undersurface of the flange.

These bearing standards as stated are similar and opposite. They have relatively flat inner faces 31 opposed to each other and flat outer faces 32 substantially parallel with the inner faces, said inner and outer faces extending perpendicularly from the top surface 11 of the bowl.

20 Bearing sockets 33 enter the body of each of the standards from both their inner and outer faces and are all in line with each other so that they lie on a common horizontal axis extending transversely across the rear of the bowl, the sockets of each standards preferably being the opposite ends of transverse bores.

25 The cover hinge member 34 is provided with a flat attaching portion 35 which is secured to the underside of the cover by screws or other fastening means and has an arm 36 directed angularly rearwardly from the attaching portion to extend a short distance downwardly therefrom in the lowered position of the cover.

30 The cover hinge member 34 extends across the full distance between the bearing standards and has integral trunnions 37 projecting in opposite directions from the extremities of its arm 36 which are pivotally received in the bearing sockets 33 opening to the inner faces of the bearing standards.

35 Projecting upwardly from the cover side of the flat attaching portion is an abutment or rib 38 integral therewith which is engageable with the rear edge of the cover and thus serves to facilitate locating the cover hinge member in its attachment to the cover.

40 The means for pivotally connecting the seat to the bearing standards comprises a pair of seat hinge members 39 one adjacent to the outer face of each bearing standard and having flat attaching portions 40 secured to the underside 45 of the seat in any suitable manner.

These seat hinge members each have an arm 41 directed angularly from the attaching portion thereof in a direction to project substantially perpendicularly upwardly toward the hinge axis when the seat is in lowered position. Integral trunnions 42 project from these arms toward each other and their adjacent bearing standards to be received in the bearing sockets opening to the outer faces thereof.

When the seat is in its lowered position shown in Figure 2, weight imparted to the seat is supported in such a manner that the trunnions of the seat hinge members are relieved of all strain or shearing stress. This desirable result is achieved through the provision of pads or bosses 43 projecting outwardly from the outer faces of the bearing standards and resting on the top face 11 of the bowl.

These pads or bosses are positioned to be engaged by the seat hinge members at areas substantially directly beneath the hinge axis of the bearing sockets so that weight applied to the seat places the angularly disposed arms 41 of the seat hinge members in compression without imparting any strain or shearing stresses on the trunnions of the seat hinge members.

An exceptionally strong construction is thus obtained which allows the hinge members to be formed entirely of plastic material.

If desired, the trunnions of the cover hinge member may be relieved of strain incidental to the application of weight onto the cover as illustrated in Figures 4 and 5, inclusive, by having portions 45 on the cover hinge member adjacent to its trunnions engage on the top surfaces of ledges 46 projecting from the inner faces of the bearing standards 30.

As best seen in Figure 5, the portions 45 on the cover hinge member are formed integral with the arm 36 thereof and extend only a short distance below the arm in the lowered position of the cover. The pads or ledges 46 on the inner surfaces of the bearing standards are integral with the standards and rest directly on the top face 11 of the bowl. These pads extend upwardly along the inner sides of the bearing standards to points adjacent to the bottom of the arm 36 and consequently close to the hinge axis to be engaged flatwise by the portions 45 on the cover hinge member in a plane parallel to the supporting surface and substantially directly beneath the hinge axis.

Thus it will be readily appreciated that weight applied to the cover is supported by the ledges or pads 46 on the bearing standards which are placed in compression between the portions 45 on the cover hinge arm and the top face 11 of the bowl, and that no strains or shearing stresses are imparted to the trunnions of either the cover hinge member or the seat hinge member.

From the foregoing description taken in connection with the accompanying drawings, it will be readily apparent that the novel design of the hinge construction of this invention makes the use of plastic material entirely practical and feasible so that all the advantages which attend the use of this new material may be fully realized.

What I claim as my invention is:

1. A toilet seat and cover hinge comprising: a cover hinge member consisting of one integral molding shaped to provide an attaching flange adapted for securing to the underside of a toilet cover along the rear edge thereof, a

rib projecting angularly from the rear edge portion of the flange and extending for the entire length of said rear edge, and coaxial trunnions projecting from the end of the rib; a pair of standards each consisting of one integral molding having a substantially flat bottom and an anchor bolt embedded therein and projecting from the bottom thereof, the upper portion of the standard having substantially parallel flat inner and outer side portions and coaxial trunnion sockets opening to said side portions; the trunnions on the cover hinge member being received in the sockets opening to the inner sides of the standards so that the cover hinge member spaces the standards; and a pair of seat hinge members each consisting of one integral molding shaped to provide an attaching flange adapted for securing to the underside of a toilet seat, an upstanding boss on the rear of the flange, and a trunnion projecting from one side of the boss; the trunnions of said seat hinge members being received in the trunnion sockets opening to the outer side faces of the standards.

2. As an article of manufacture, a toilet cover hinge part comprising: a one piece molding having angularly disposed portions, one of which is a substantially flat attaching flange securable to the underside of a toilet cover along the rear edge thereof with the other portion forming a downwardly directed supporting rib; and coaxial trunnions projecting from the opposite ends of the rib forming portion.

3. A hinge construction for toilet seat and cover members comprising: a pair of bearing standards; an anchor bolt embedded in each of said standards and projecting from the bottom thereof to provide means for securing the standard to a toilet bowl; said bearing standards having holes extending transversely through the upper portion thereof; a one piece hinge part securable to one of said members; aligned trunnions on the ends of said hinge part pivotally received in the holes of the bearing standards but occupying less than the full length of said holes; a pair of hinge parts securable to the other member, said last named hinge parts each having a trunnion projecting from one side and pivotally received in the unoccupied portion of the transverse hole in the adjacent bearing standard.

4. A hinge construction for toilet seat and cover members comprising: a pair of bearing standards; an anchor bolt embedded in each of said standards and projecting from the bottom thereof to provide means for securing the standard to a toilet bowl; said bearing standards having holes extending transversely through the upper portion thereof; a one piece hinge part securable to one of said members; aligned trunnions on the ends of said hinge part pivotally received in the holes of the bearing standards but occupying less than the full length of said holes; a pair of hinge parts securable to the other member, said last named hinge parts each having a trunnion projecting from one side and pivotally received in the unoccupied portion of the transverse hole in the adjacent bearing standards; and ledges on the bearing standards in position to have the lowermost of said hinge parts by which the seat is hinged mounted rest thereon when the seat is in its lowered position.

HAROLD D. WATSON.
